UNITED STATES PATENT OFFICE

2,576,788

FIBER RECOVERING MACHINE

William L. Hannold, Alpine, and James J. Griffith, Friona, Tex.

Original application November 8, 1943, Serial No. 509,468. Divided and this application May 26, 1947, Serial No. 750,540

1. Claim. (Cl. 19—12)

This invention relates to new and useful improvements in fiber recovering machines, and the present application is a division of our U. S. application for Fiber Cleaning Machine, Serial No. 509,468, filed November 8, 1943, now abandoned.

The present invention relates particularly to machines for recovering the fiber from lechuguilla, meguey, palma and other plants which are found in abundance in the southwestern section of the United States and portions of Mexico.

The primary object of the present invention is to provide an automotive machine of the character described adapted for use in the field and comprising a motor vehicle chassis having mounted thereon a unique combination and arrangement of means and mechanisms for successively splitting the butts of the plants for separating the leaves thereof, then crushing the leaves to loosen the pulp and bark thereon, then successively combing opposite end portions of the leaves for completely removing the bark and pulp from the fiber, and then delivering the fiber or decorticated leaves from the machine at the rear of the latter.

Another object of the invention is to provide a fiber recovering machine of the above kind which is simple in construction and highly efficient in operation, and which may be manufactured at low cost.

Other objects and advantages of the present invention will become apparent from the following description when considered in connection with the accompanying drawings, in which:

Figure 1 is a side elevational view of a machine constructed in accordance with the present invention.

Figure 2 is an enlarged transverse sectional view, taken substantially on line 2—2 of Figure 1.

Figure 3 is a fragmentary diagrammatic view in side elevation, of the leaf crushing and conveying means.

Figure 4 is a fragmentary diagrammatic view in top plan, of the leaf crushing, conveying and scraping means.

Figure 5 is a diagrammatic view of substantially the complete assembly.

Referring in detail to the drawings, the illustrated embodiment of the present invention comprises an elongated rectangular skeleton frame 5 which is mounted longitudinally of and on the frame of a conventional motor vehicle chassis 6 having front steering and supporting wheels W and rear traction wheels W'. A feed table top 7 is mounted on the forward end portion of the

frame 5 so as to overlie the front power plant 8 and the driver's seat S of the motor vehicle chassis. Mounted longitudinally on one side portion of the table top 7 is a toothed drum or cylinder 9 arranged within a housing 10. As shown in Figure 2, the butts 11 of the plants 12 on the table top 7 are inserted by the operator in the housing 10 so that the toothed cylinder 9 will cut said butts and thereby separate the leaves of said plants.

Mounted on the frame 5 at the rear end of table top 7 for receiving the leaves from the latter, is an endless conveyor 13 which delivers the leaves to a pair of crushing rolls 14 journaled transversely on the frame 5.

Mounted in the rear portion of the frame 5 is a suitable decorticating mechanism which may be of a well-known type and which includes a front scraping unit 15 which receives the crushed leaves from the rolls 14 and delivers said leaves to a rear scraping unit 16 after cleaning one end portion of the leaves.

The unit 15 includes co-acting upper and lower endless conveyor chains 17 and 18 which are mounted longitudinally in the frame 5 and which are trained over sprocket wheels 19. As best shown in Figure 3, the chain 18 extends forwardly beyond the chain 17 for receiving the leaves from the crushing rolls 14. The opposed or adjacent runs of the chains 17 and 18 receive and secure the butt end portion of the leaves therebetween, and suitable tighteners 20 are provided for these chains. The unit 15 further includes a pair of upper and lower endless scrapers or combers 21 which travel transversely of the frame 5 and extend from a point adjacent the chains 17 and 18. The scrapers 21 may comprise endless sprocket chains which are trained over pairs of sprocket wheels 22 fixed on longitudinal shafts 23, and substantially channel-shaped combs 24 connecting the chains. The endless scrapers 21 are adapted to receive one end portion of the leaves therebetween, as said leaves are carried rearwardly by the chains 17 and 18.

The unit 16 comprises co-acting upper and lower endless belts 31 which are trained over pulleys 32 in the frame 5. The opposed runs of the belts 31 are adapted to receive and grip therebetween the cleaned end portions of the leaves delivered from the unit 15. Suitable tighteners 34 are provided for the belts 31, and said belts constitute means for conveying the other or uncleaned end portions of the leaves between a pair of upper and lower endless scrapers or combers 36 of the unit 16. The scrapers 36 are substan-

50 tially the same as the scrapers 21, and are trained over pairs of sprocket wheels 37 fixed on longitudinal shafts 38. The scrapers 36 are adapted to receive one end portion of the leaves therebetween, as said leaves are carried rearwardly by the belts 31. The unit 16 is

cially similar in construction and operation to the scrapers 21 of the unit 15. Endless conveyors 38 receive and support the end portions of the leaves which have just been cleaned by the scrapers 36, for delivering the fibers straight and even at the rear end of the machine in conjunction with the belts 31.

The apparatus includes a main drive shaft 39 having suitable driving connections with the cylinder 9, the upper roll 14, a shaft of the lower scraper 21, a shaft of the upper scraper 36, and a shaft of the lower belt 31 as shown in Figure 5. As is also shown in the latter figure, the rolls 14 are intergeared, and the shaft of the lower roll 14 is operatively connected to a shaft of conveyor 13. In addition, lower chain 18 is driven from the shaft of lower roll 14, upper chain 17 is driven from the shaft of upper roll 14, adjacent shafts of scrapers 21 are intergeared, adjacent shafts of scrapers 36 are intergeared, conveyors 38 are driven from a shaft of belt 31, and conveyors 30 are respectively driven from shafts of the respective belts 31. The main drive shaft 39 of the apparatus is releasably connected to the drive shaft of the engine 40 of power plant 8 by means of a power take-off 41 and a clutch 42 which has a standard clutch lever 42'. Thus, the apparatus may be disconnected from the engine 40 when not in operation, for permitting said engine to drive the vehicle from one point to another through the usual transmission 43, with the apparatus idle. When the machine is brought to a standstill, the transmission 43 may be placed in neutral and the clutch 42 may be engaged by actuating the clutch lever 42' to drive the apparatus.

In operation, the plants are suitably delivered to the table top 7, and the operator, standing at the side of the table top which is remote from the cylinder 9, grasps the plants and inserts the butt ends 11 thereof into the housing 10 for engagement by the toothed cylinder 9. The cylinder 9 cuts the butt end portions of the plants to separate the leaves thereof, whereupon the operator pushes the leaves onto the conveyor 13, by which they are fed to the crushing rolls 14. The rolls 14 deliver the crushed leaves to the unit 15, the chains 17 and 18 receiving and gripping the butt end portions of the leaves therebetween. The chains 17 and 18 move the leaves rearwardly between the scrapers 21 so that the combs 23 remove the pulp and bark from the leaves. The leaves are then delivered to the unit 16 where the scraping process is repeated on the other end portions of the leaves.

As the specific construction of the decorticating mechanism forms no part of the present invention per se, it is believed unnecessary to more specifically illustrate and describe the same herein, particularly as such mechanism is of a generally old and well-known type. It will be seen that the machine may be readily driven to the

point in the field where the plants are gathered, and that the machine may then be utilized at this point for operating upon the plants to separate and decorticate the leaves thereof, finally delivering the fiber or decorticated leaves from the machine at the rear of the latter. The removed bark and pulp may be discharged directly onto the ground so that no disposal problem in connection therewith is presented. The clean fiber may be suitably collected and transported from the field in relatively great quantity, thereby doing away with the necessity of transporting the uncleared leaves to a stationary plant in which the operations are employed and where the problem of disposal of the bark and pulp is presented.

From the foregoing description, it is believed that the construction, operation and advantages of the present invention will be readily understood and appreciated by those skilled in the art. 20 Minor changes in details of construction are contemplated, such as fall within the scope of the invention as claimed.

What we claim is:

25 In a portable fiber recovering machine, the combination with a conventional motor vehicle chassis having a driver's seat and including a front power plant provided with a power take-off, of an elongated rectangular skeleton frame mounted on the frame of said chassis and extending substantially from end to end thereof, a horizontal table top mounted on the forward portion of said skeleton frame and extending over the power plant and the driver's seat, a cutting device mounted at one side of said table top for 30 cutting the butts of plants to separate the leaves thereof, a crushing device mounted on the skeleton frame rearwardly of said cutting device, a conveying device mounted on the frame at the rear of said table top to deliver the separated leaves to said crushing device, a decorticating mechanism mounted in the rear portion of said skeleton frame to receive the crushed leaves from the crushing device and decorticate the same, a main drive shaft journaled on and disposed longitudinally of the chassis frame and operatively connected to said devices and said mechanism, and manually operable means for selectively connecting said drive shaft to or disconnecting the same from said power take-off.
